10 Claims. (Cl. 120—48)

This invention relates to a fountain pen, and more particularly to one of the type wherein a reservoir, located toward the rear of the pen and having a volume typically constituting the major portion of the entire pen volume, may be filled with ink, portions of which may thereafter from time to time be transferred forwardly to a smaller space or ink-collector communicating through capillary and surface flow with the writing tip. Pens of that type have been disclosed in various prior patents to me, among which may be mentioned Nos. 2,724,366 and 2,753,846.

In preferred constructions such a pen has a fluid-transfer passage extending between the ink-collector and a point within the reservoir adjacent the rear end of the latter. During filling such a pen is held with its rear end up and its front end immersed in an external ink supply, and the wall of the reservoir is repetitively deformed to reduce its volume and to expel air through the passage and ink-collector; after each such deformation the wall is allowed to restore itself to its normal configuration, each restoration resulting in the sucking up, through the passage, of ink, which from the then-raised rear end of the passage falls into the intra-reservoir space around the passage, that rear end always remaining above the level of the ink in the reservoir during the process. During a transfer of ink from the reservoir to the ink-collector such a pen is held with its front end up so that the rear end of the passage is immersed within the ink in the reservoir, and the wall of the reservoir is progressively deformed until enough ink has been forced upwardly through the passage to fill or substantially to fill the ink-collector.

In preferred constructions such a pen is provided with a valve normally closing the transfer passage and thereby normally insuring the retention of ink in the reservoir under all conditions of pen orientation, relative internal and external pressures etc. Toward this end I disclosed in Patent No. 2,724,366 a valve, located at the rear end of the passage, which may be opened by deformation of the wall of the reservoir at that longitudinal region; in that construction, however, that deformation, although usually sufficient for the transfer of ink from reservoir to ink-collector, is inefficient in invoking the filling of the reservoir, and the user's tendency during filling is therefore to call his other hand into play to effect an independent repetitive deformation more forwardly along the reservoir wall. On the other hand in Patent No. 2,753,846 I disclosed a valve located near the longitudinal center of the reservoir and of such a construction that the wall deformation required to open it is a deformation which rather efficiently invokes the filling action; this location of the valve, however, results in the intervention of a substantial length of passage between it and the rear end of the passage, in which length ink may remain undesirably immobilized for substantial periods of time.

Furthermore, in each of these constructions there is required the securing of the valve against the wall of the reservoir at a point removed from that end of the reservoir which is open prior to final assembly, entailing a burdensome locating and securing task. Still further, valves of either of those constructions are completed and capable of being tested only after their assembly in the reservoir. Still further, valves of either of those constructions are not characterized by the safety feature of being further biased to closed condition by excess pressure which may be generated from time to time in the reservoir.

2

It is an object of the present invention to provide a pen of the type described wherein the valve is located to avoid the immobilization of ink in any appreciable length of the passage, yet is opened by a wall deformation which efficiently invokes the reservoir-filling action.

It is another object to provide for such a pen a valve which requires no securing to the wall of the reservoir. It is another object to provide a valve which may be completely and fully tested prior to any assembly involving the reservoir. It is another object to provide a valve of exceptional simplicity and durability. It is another object to provide a valve which is subjected to additional bias to closed condition by any excess pressure in the reservoir.

It is another object to provide for such a pen improved and simplified valve-actuating means and arrangements.

Another object of the invention is to provide an ink-collector of improved space efficiency and other characteristics.

Another object is to provide a generally improved pen of the type described. Still other and allied objects will appear from the following description and the appended claims.

In a principal aspect the invention involves the use of a valve located at the rear of the fluid-transfer passage and thus adjacent the rear end of the reservoir, but controlled by the transverse configuration of a longitudinally intermediate portion of the reservoir wall—e.g., openingly responsive to a transverse deformation of such a wall portion. Alternatively stated, it involves the use of a longitudinally movable closure member associated with the passage at the rear end of the latter, but positionally controlled by the transverse configuration, or motionally responsive to the transverse deformation, of such an intermediate wall portion. Somewhat more specifically, it involves the use of a sleeve surrounding and longitudinally slidable on a rear portion of the passage-forming tube and valve means at the end of the tube and operated by the sleeve.

In another aspect the invention involves the use of a passage in the form of a tube extending from the finger-piece of the pen to a point within the reservoir remote from the finger-piece and a valve, operable from exteriorly of the reservoir, supported wholly by the tube. In still another aspect it involves the arrangement of the valve so that excess pressure within the reservoir exerts on it an additional closing bias.

In a particular aspect the invention involves, in various forms, a resilient valve-actuating means characterized by longitudinal and transverse dimensions which vary inversely to each other and transversely compressible to actuate the valve.

In another particular aspect the invention involves, in various forms, an ink-collector whose rear end portion is operatively free of transverse subdivision but whose forward portion is transversely subdivided into a limited number of separate but functionally parallel paths each of small maximum transverse dimension.

Other aspects of the invention will be apparent from the following detailed description of my invention herein-after set forth.

In that description reference is made to the accompanying drawings, in which:

FIGURE 1 is a cross-sectional view, as seen looking from the bottom and with the front end of the pen upwardly directed, of a fountain pen in which my invention has been embodied in one form, the fractionally cylindrical member forming the point of the pen appearing in elevation;

FIGURE 2 is a cross-sectional view taken along the line 2—2 of FIGURE 1;

FIGURE 3 is an enlarged cross-sectional view taken along the line 3—3 of FIGURE 1;

FIGURE 4 is a cross-sectional view taken along the line 4—4 of FIGURE 1;

FIGURE 5 is a cross-sectional view similar to the lower-shown portion of FIGURE 1 but illustrating a modification of the valve-operating and -actuating means;

FIGURE 6 is a cross-sectional view similar to FIGURE 1 but illustrating a fountain pen in which my invention has been embodied in a form modified in various respects from that shown in FIGURE 1;

FIGURE 7 is a cross-sectional view taken along the line 7—7 of FIGURE 6;

FIGURE 8 is an enlarged cross-sectional view taken along the line 8—8 of FIGURE 6; and

FIGURE 9 is a cross-sectional view taken along the line 9—9 of FIGURE 6.

Reference is first invited to FIGURES 1 through 4. Therein the portion of the pen to which the other elements are assembled is a generally cylindrical finger-piece 10, which may taper toward the front of the pen and which is provided with a longitudinal bore 11 of substantial diameter extending throughout all excepting the rear portion of the finger-piece. Into the front part of the bore there may be inset the point 1 of the pen, which in form may approximate a cylinder which is very obliquely truncated so that its top (seen to the right in FIGURE 1) greatly overhangs its bottom (seen to the left) and which is circumferentially interrupted along its bottom so as to be diametrically resilient; in a central part of its top it may be provided with a small hole 2 from which there extends forwardly a cut 3 separating the entire forward portion of the point into two nibs 4 terminating at the front of the point (seen at the top in FIGURE 1) in respective halves of the actual writing tip 5. The fractionally cylindrical point may be inset into the forward portion of the bore 11; if desired, the internal diameter of the point may be made essentially similar to that of the bore and the bore then locally enlarged, by almost the thickness of the point material, in its area against which the point will lie to result in a slight shoulder 12 around the sides and top of the bore against which the rear end of the point may abut. The finger-piece 10 may if desired be obliquely truncated so as almost fully to surround the point 1, as to which it will then serve as a hood.

The finger-piece 10 is desirably transparent, and may for example be molded or otherwise formed of a transparent plastic material.

The greater longitudinal portion of the bore may be disposed to the rear of the point 1 (e.g., to the rear of the shoulder 12), and within both this portion and the point 1 may be located an ink-collector 15. In the form of the invention shown in FIGURES 1 through 4 the ink-collector may be constituted by the inner surfaces of the point 1 and of the bore 11, together with a bundle 16 of capillary tubes, for example of stainless steel, press-fitted within that point and that bore. At their forward extremities the tubes of the bundle 16 may terminate in an oblique plane roughly coincident with the forward edge of the fractionally cylindrical point 1. Desirably there will be fluid communication between the rear portions of the tubes of the bundle 16 and of the interstices therebetween and therearound; this is readily provided, for example, by making the rear end of the bore 11 of a wide-V-shaped section against which only the outermost points of the outer tubes of the bundle can abut, and taking care that the inner tube (or tubes) shall not very appreciably rearwardly overhang the outer tubes, the result being a space 14 at the rear of the ink-collector 15 through which the abovementioned fluid communication is provided for. By way of example the bundle 16 has been illustrated as formed of six outer and one inner tube, but this is not intended as limitative. The bundle 16 may cooperate with the bore 11 to frictionally grip the point 1 and thus to insure its retention in proper position. The individual tubes of the bundle 16 may for example be of the order of .060" outside, and .040" inside, diameters.

Even though the ink-collector 15 (including the space

14 as well as the bores of and the interstices between and around the tubes) be full of ink and the front end of the pen be downwardly directed for writing, the small lateral dimensions of the bores and interstices will, so long as fluid flow from the rear into the space 14 is cut off, limit the flow of ink out of the ink-collector to capillary and surface flow only, toward the front ends of the tubes and in turn to the nibs 4 of the point 1. At the same time those small lateral dimensions restrict the upward flow through the ink-collector of air seeking to substitute itself for the ink used in the writing—which flow of air could, if not restricted, defeat the abovementioned limitation on the outflow of ink from the ink-collector.

The reservoir 20 of the pen lies to the rear of the finger-piece 10, typically having a length of the order of twice that of the finger-piece. It may be formed by force-fitting, with cement, the mouth of an elongated relatively thin-walled barrel 21 about the rear end portion of the finger-piece, which portion may at an external shoulder 13 on the finger-piece be reduced in radius, below the radius of the central portion of the finger-piece, by the thickness of the barrel wall. The barrel may be a stiff but transversely deformable one-piece element, closed at its rear end, and is preferably transparent; it should remain free of cracking tendencies during a long life and its wall should be and remain impervious to water-vapor passage. To achieve these several specifications I prefer to use for the material of the barrel a non-cellulosic plastic, such as that currently available from Eastman Kodak Company under the trade name "Tenite-polypropylene," but no unexpressed limitation thereto is intended.

Means are provided for conducting fluid between the ink-collector 15, specifically the rear portion or space 14 thereof, and a point within the reservoir 20 adjacent the rear end thereof. For this purpose there may be force-fitted from the rear through a central hole in the rear portion of the finger-piece 10 a small-diameter fluid-conducting transfer tube 25, for example of stainless steel, the exposed portion of which extends from the finger-piece rearwardly to a point which after the subsequent assembly of the barrel 21 to the finger-piece will be adjacent to the rear end of the barrel 21.

The transfer tube is intended to be open, for the transfer of fluid between the ink-collector and the reservoir, at appropriate times only. In order that it be normally closed, yet opened at such times, a valve 30 is suitably associated with it. According to the invention this valve is located at the rear end of the transfer tube 25, in order that when the pen is held in writing position essentially the entire length of the tube 25 remains in free communication with and above the ink-collector 15; this in effect joins the space within the transfer tube 25 to the ink-collector, so that in the intended writing use of the pen any ink initially present in the tube 25 becomes simply part of the aggregate collected ink available for capillary and surface flow to the nibs 4 of the point 1.

The valve 30 may be formed by a narrow cap member 31 whose mouth surrounds the rear end portion of the transfer tube 25 (through the intermediary of a valve-operating sleeve 35 hereinafter described), which from that mouth extends rearwardly substantially beyond the rear end of that tube, in the sides of which beyond that end are provided fluid-conducting holes 32, and in the inner recess of which is retained a seat member 33. This seat member may be in the form of a slightly tapered plug inserted rearwardly, thicker extremity first, as far as possible into the cap member; an axial hole 34 in the end of the cap member relieves any entrapment of air which might otherwise cause complications during attempted full insertion.

In the structure of FIGURES 1 through 4 the cap member 31 is biased forwardly, so as normally to bring the forward end of the seat member 33 into abutment against the rear end of the transfer tube 25 and thus to close the valve, by a resilient rubber pad 39 normally at least slightly compressed between the rear surface of the end

of the cap member and the interior surface of the closed rear end of the barrel 21. This pad 39, although effective in the longitudinal direction to bias the valve 30 to closed condition, effects no significant contribution to the lateral support of the valve; that support is simply by the transfer tube 25 (and through it by the finger-piece 10). The pad 39 may simply be cemented to the end of the cap member (after the insertion into the latter of the seat member 33, so that it is then permissible to seal off the hole 34). When the barrel 21 is later assembled over the transfer tube and valve it passes freely thereover, with no requirement for the interior assembly of any parts to, or even their compression to fit within the bore of, the barrel.

The valve-operating member is the sleeve 35 above referred to, which surrounds the transfer tube from near the middle of the exposed part of that tube almost to its rear end, the mouth of the cap member 31 being force-fitted over the rear end of the sleeve so as to occupy the position stated in the second preceding paragraph. At the forward end of the sleeve 35 there may be soldered or otherwise secured about it a washer 36, forming thereon a terminal flange. The sleeve 35 is slidable along the transfer tube 25, thus permitting a limited displacement of the sleeve and cap member rearwardly against the force of the biasing pad 39, which displacement will serve to open the valve 30.

The valve 30 is controlled by the transverse configuration of a longitudinally intermediate portion of the reservoir wall—i.e., of such a portion of the barrel 21. More specifically, the valve is closed when the transverse configuration of that barrel portion is circular, but the valve is openingly responsive to a transverse deformation of that barrel portion. In the structure of FIGURES 1 through 4 the means through which the valve is thus controlled, or through which it is made thus responsive, is a resilient annulus or "doughnut" 40, for example of rubber. In this annulus, along a diametrical line lying in its central plane, are formed two holes which just freely surround the tube 25, on which tube the annulus is supported immediately in front of the flanged forward end of sleeve 35. Immediately in front of the annulus a washer 26 is secured about the tube 25 to form thereon a flange. The overall dimension of the annulus is preferably minutely less than the internal diameter of the barrel 21, so that there will ordinarily be no transverse compression of the annulus.

In the absence of transverse compression of the annulus 40 the valve 30 will be closed under the influence of the biasing pad 39. If, however, the barrel 21 be deformed by a squeezing pressure against its sides which deforms not only it but also the annulus, the resulting elongation of the annulus in the direction longitudinal of the pen will force the flange 36 and with it the sleeve 35 rearwardly against the force of the pad 39, thereby opening the valve and rendering the transfer tube 25 open for the conduction of fluid. Opening of the valve to a modest degree—sufficient, however, for effective fluid transfer—will have occurred when the deformation of the barrel is minor; progressive further deformation will of course simply open the valve further.

While the deformation of the barrel is proceeding the cubic space within the reservoir 20 is being progressively reduced, so that fluid will be progressively expelled from the reservoir through the transfer tube and ink-collector. In turn upon a release of the squeezing pressure the deformation of the barrel will progressively reduce, and the cubic space within the reservoir will progressively increase, under the influence of the strong restoring force of the barrel; the valve still being open, fluid will be progressively drawn into the reservoir through the ink-collector and transfer tube—this action continuing until the deformation has been substantially undone and the valve therefore re-closed.

In the filling of the pen it will be held with its forward end downwardly directed and immersed in an external ink

supply. Whether the quantity of ink in the reservoir 20 be little or much, the valve 30 will be elevated to above the level of that ink; accordingly the fluid expelled from the reservoir during each deformation of the barrel and annulus will be air. On the other hand the immersion of the forward end in ink causes the fluid drawn into the reservoir during each release of the deformation to be ink, which from the valve will spill into the then-lower principal portion of the reservoir. An alternation of deformations and releases will serve progressively to exchange the air in the reservoir for ink, and thus to fill the reservoir. The passage of fluid through the ink-collector and transfer tube during this process thoroughly flushes and thus cleans them.

Upon that closure of the valve 30 which occurs at the cessation of filling (whether that filling be a major or a minor one) both the ink-collector and the therewith-communicating transfer tube will be full of ink. This collected ink will be held therein, despite the raising of the forward end of the pen from its immersion, by the action of the small lateral dimensions characterizing the ink-collector, mentioned above; the ink will, however, pass out therefrom in capillary and surface flow to the nibs 4 of the point 1, as ink is consumed at the tip 5 in writing with the pen.

When not only the transfer tube but also the ink-collector have been emptied by that consumption, the pen may be held approximately vertical with its front end up. Whether the quantity of ink in the reservoir 20 be little or much, the valve 30 will be immersed in that ink; accordingly the fluid expelled by the transfer tube 25 from the reservoir during a deformation of the barrel and annulus will be ink. It is expelled into the ink collector, and will not leave the pen unless and until that ink-collector has been filled as far as the level of the bottom front end (seen in FIGURE 1 as the left top end) of the finger-piece 10. In practice a single squeeze is more than sufficient to fill the ink-collector by transfer from the reservoir; that squeeze will be effected gradually, and stopped when the level of ink in the ink-collector (observed through the transparent finger-piece) approaches or just reaches the level mentioned in the preceding sentence. It is of course true that were the release also to be effected very gradually, the transferred ink could and would re-transfer back into the reservoir; any substantial such re-transfer is readily avoided by effecting the release abruptly, so that the valve 30 is closed before any significant re-transfer can occur. The abrupt valve closure may leave the pressure within the reservoir a slightly less-than-atmospheric one, but this is altogether harmless.

In a typical pen as thus described the reservoir and ink-collector capacities are essentially fully usable; they may typically be of the orders of 6 cc. and of 0.6 cc. respectively, so that the overall ink capacity of the pen is many times the actually usable capacity of a conventional pen. The reservoir is proofed against leakage by the valve, which is positive in action and moreover is closely responsive to pressure within the reservoir (i.e. exerted on the outer surface of the cap member 31) so that, in contrast to usual pens, the effect of increased internal pressure or of decreased atmospheric pressure is even further to secure the reservoir against leakage. The distinct ink collector, although ink can if desired be ejected from it by a deliberate abruptly terminated rapid forward axial movement of the pen, will release ink otherwise only when the point is downwardly directed—and then only in the capillary and surface flow which is an incident of writing, and which is quite uninfluenced by pressure or temperature variations (certain of which can block the ink flow from even well-filled pens of ordinary construction).

In FIGURE 1 the central plane of the annulus 40 is shown as extending (in its transverse direction) from side to side of the pen and the regions at which the barrel

21 should be squeezed in order to deform the annulus as well as the barrel therefor as being at the sides of the barrel; it will be understood, however, that this is by way of example only. Although those regions to be squeezed for valve opening are apparent due to the transparency of the barrel, they may if desired be specially designated as by dots (for example, of a color such as red) enamelled or otherwise fixed on the outside of the barrel opposite the points of closest adjacency of the annulus, as indicated at 22 in FIGURE 1.

FIGURE 5 illustrates a limited modification of the structure of FIGURES 1 through 4 in respect of the valve-biasing, -operating and -actuating means. In it the biasing pad 39 is omitted; the annulus, now designated as 40', is stressed a little into slightly elliptical configuration with major axis longitudinal of the pen (being for example made slightly larger than the annulus 40 so that its now-minor-axis dimension will still minutely less than fill the bore of the barrel 21); and the washers or flanges 26 and 36 are replaced by glued joints (27 and 37 respectively) of the stressed annulus to the tube 25 and sleeve 35 respectively (the sleeve being, for the purpose, somewhat forwardly extended to pass through a now-enlarged rear hole in the annulus). The slightly stressed annulus, seeking to restore itself to unstressed circular configuration, now additionally performs the function of biasing the sleeve 35 forwardly and thus the valve 30 to closed condition; otherwise the operation and use of the pen of FIGURE 5 is quite similar to that of the pen of FIGURES 1 through 4.

In FIGURES 6 through 9 I show a pen in which modifications from the pens of earlier figures are made in respect both of the ink-collector and of the valve-actuating means—it being understood, however, that either of these modifications might be employed without the other.

Within the finger-piece (now designated as 10') the ink-collector (now designated as 15') is changed by the elimination of the bundle 16 of tubes and by the use, within the fractionally cylindrical point 1, of a plug 17 provided with suitable capillary- and surface-flow paths. The bore of the finger-piece (that bore now being designated 11') may throughout its length be approximately of a diameter corresponding to the outside diameter of the point 1, although a very slight reducing shoulder 12' a little to the rear of the normal position of the rear of the point 1 may if desired be employed to guard against substantial over-insertion of the point and plug. The plug, which may be of either a transparent or an opaque plastic, may be generally in the form of a cylinder which may fit within the point 1, but in the circumferential region where the point is interrupted it may if desired be locally enlarged (see FIGURE 8) to have a radius similar to the outside radius of the point. At its forward end the plug 17 may terminate in an oblique plane similar to that in which the bundle 16 of earlier figures terminates. While at its rear end the plug 17 throughout its cross section may terminate in a normal-to-axis plane approximately coincident with that in which the point 1 terminates, that rear end may if desired be bevelled throughout all but its very bottom portion, for example at about 45° to the axis as shown in FIGURES 6 and 7, to result in a minimum rearward extent at the top of the pen. The plug 17 (and if desired the forward portion of the bore 11') may be minutely tapered toward the rear of the pen (not shown because of minuteness) so that the plug will act as a wedge for fixing the longitudinal position of the point and thereby controlling the extent of forward exposure, and thus the resilience of, the nibs 4.

The capillary- and surface-flow paths mentioned above as being provided in the plug 17 may comprise a central axial hole 18 (for example of the order of .030" diameter) and at least one groove 19 (for example of a similar order of depth) extending longitudinally along and

throughout the length of the top portion of the plug and communicating with the hole 2 from which the cut or slit 3 extends to the tip of the point 1.

This modified ink-collector, which has the advantages of somewhat more net ink capacity and of somewhat simpler and less expensive construction, I have found thoroughly satisfactory in operation. The restricted-cross-section paths (now 18 and 19) have an aggregate cross section very much less than the corresponding paths in the pen of earlier figures, and thereby provide compensation for the facts that their lengths are now shorter (though still somewhat greater than the diameter of the bore 11') and that above them (during an orientation of the pen for writing) there may now be an appreciable column of ink—i.e., that in the elongated space now designated as 14'—not subdivided into restricted cross sections. If the rear end of the plug 17 be bevelled as described above, substantially the entirety of the ink in the space 14' is available for flow, during the writing, through the hole 18 and groove 19, since the pen is then customarily held at an angle of more than 45° from the horizontal.

In the pen of FIGURES 6 through 9 the general arrangement of the valve-operating sleeve 35 may be as in FIGURE 5, but the valve-actuating means is changed from the annulus of that figure to a metallic spring. This spring, which may be formed of wire of stainless steel or other corrosion-resistant wire and is designated as 45, may at one end be looped and secured about the sleeve 35 somewhat rearwardly of the forward end of that sleeve; may extend therefrom diagonally forwardly to a region closely adjacent the barrel wall, where a single small loop 46 generally parallel to that wall may be formed in it; may extend from the loop 46 diagonally forwardly to have a loop 47 formed in it and secured about the tube 25 somewhat forwardly of the forward end of the sleeve 35; may extend therefrom diagonally rearwardly to a region closely adjacent the barrel wall at a point transversely opposite to the loop 46, at which region another small loop 48 parallel to the barrel wall may be formed in it; and may extend from the loop 48 diagonally rearwardly to have its second end looped and secured about the sleeve 35 immediately adjacent to its first end. In fabrication the spring 45 may be formed with its three intermediate loops 46, 47 and 48, and with its ends looped and secured about the sleeve 35 (as by soldering), and may initially be adjusted so that the outer dimension across the loops 46 and 48 is slightly greater than the inside diameter of the barrel; in the positioning of the sleeve 35 on the tube 25 the loop 47 will be first slipped around the tube 25. With the sleeve 35 in its valve-closing position, the loop 47 will be moved forwardly sufficiently to contract the outer dimension across loops 46 and 48 to minutely less than the inside barrel diameter, and thereupon secured (as by soldering) to the tube 25.

Like the annulus 40 or 40' of earlier figures, the quadrilaterally arranged spring 45 forms a resilient means which is characterized by longitudinal and transverse dimensions which are inverse functions of each other, and which has its end portions in force-transmitting relationships to the tube 25 and valve-operating sleeve 35 respectively. Like the annulus 40' of FIGURE 5, the spring 45, secured in place (with the valve closed) in somewhat elongated condition, tends to contract longitudinally and thereby biases the valve into closed condition; further as in the case of the annulus 40', it is a further elongation, by deformation of the barrel across an appropriate diameter (now the diameter 46-48) which serves to open the valve.

While I have disclosed my invention in terms of particular embodiments thereof it will be understood that I intend thereby no unnecessary limitations. Modifications in many respects will be suggested by my disclosure to those skilled in the art, and such modifications will not

necessarily constitute departures from the spirit of the invention or from its scope, which I undertake to define in the following claims.

I claim:

1. In a fountain pen having in its forward portion a point and an ink-collector from which during writing ink may flow to the point, the combination of an elongated reservoir positioned to the rear of the ink-collector and having a stiff but transversely deformable wall, fluid-conducting means extending between the ink-collector and a point within the reservoir adjacent the rear end of the reservoir, valve means at the rear end of and controlling the conduction of fluid through said fluid-conducting means, means within the reservoir at a longitudinally intermediate portion thereof for sensing transverse deformation of the adjacent portion of the reservoir wall, and longitudinally extending mechanical means coupling said valve means to sensing means for operation of said valve means upon deformation of said reservoir wall portion.

2. In a fountain pen having in its forward portion a point and an ink-collector from which during writing ink may flow to the point, the combination of an elongated reservoir positioned to the rear of the ink-collector, a tube, extending to have an end at a point within the reservoir remote from the ink-collector, through which fluid may be conducted between the ink-collector and the reservoir, a sleeve surrounding and longitudinally movable on the portion of the tube adjacent said end thereof, valve means at said end of and effective on said tube and operated by said sleeve upon longitudinal movement of said sleeve, and means for moving said sleeve longitudinally in response to transverse deformation of a longitudinally intermediate portion of the reservoir wall.

3. In a fountain pen having in its forward portion a point and an ink-collector from which during writing ink may flow to the point, the combination of an elongated reservoir positioned to the rear of the ink-collector, fluid-conducting means extending between the ink-collector and a point within the reservoir adjacent the rear end of the reservoir, and a valve adjacent that end of the reservoir controlling said fluid-conducting means and having a longitudinally movable operating portion exposed within and biased to valve-closing position by excess pressure within the reservoir.

4. In a fountain pen having a point and an ink-collector from which during writing ink may flow to the point, the combination of an elongated reservoir positioned to the rear of the ink-collector and having a stiff but transversely deformable wall, a tube, extending into the reservoir through which fluid may be conducted between the ink-collector and the reservoir, valve means within the res-

ervoir associated with and controlling the conduction of fluid through said tube, and resilient means, located within the reservoir and characterized by longitudinal and transverse dimensions which are inverse functions of each other and having end portions in force-transmitting relationships to said tube and said valve means respectively, transversely compressed by the reservoir wall upon transverse compression of that wall to subject said valve means to movement relative to said tube.

5. The subject matter claimed in claim 4 wherein said movement of said valve means is an opening movement, and further including means independent of said transversely compressible means for imparting a closing bias to said valve means.

10 6. The subject matter claimed in claim 4 wherein said movement of said valve means is an opening movement and wherein said transversely compressible means in the absence of externally imposed compressible is longitudinally extended whereby to impart a closing bias to said valve means.

7. The subject matter claimed in claim 4 wherein said transversely compressible means comprises a resilient annulus.

8. The subject matter claimed in claim 4 wherein said transversely compressible means comprises a quadrilaterally arranged spring.

25 9. The subject matter claimed in claim 1 wherein said valve means is normally closed and wherein the recited operation thereof is an opening thereof.

10. The subject matter claimed in claim 1 wherein said valve means comprises a closure member normally biased forwardly against the rear end of said fluid-conducting means and wherein the recited operation of said valve means is a movement of said closure member away from that rear end.
